HALTER

Valerie Nagy, Forest Hills, N. Y.

Application August 2, 1945, Serial No. 608,414

5 Claims. (Cl. 2—42)

1

This invention relates to halters, the term "halter" being arbitrarily employed herein to denote the scanty bust covering upper part of a two piece outer garment.

Heretofore halters have looked attractive only when worn on youthful figures, since a halter designed simply to be draped on the bust neither provided the molding and uplift required by a sagging bust nor sufficient control to prevent exposure thereof. On the other hand, if the halter was fashioned along the lines of a scanty brassière (i. e., without a band secured to the bottom edges of the bust cups) to provide the necessary molding, uplift and control, the undersides of the bust shortly became exposed. This, of course, cannot be countenanced in an outer garment.

It is an object of my invention to provide a halter generally resembling a brassière, and therefore affording the proper molding, uplift and control, but so constructed as to prevent exposure of the undersides of the bust even upon vigorous movement of a wearer.

It is another object of my invention to provide a halter of the character described in which the means for preventing exposure of the undersides of the bust may be manipulated to enhance the uplift and control of the basic brassière design.

It is a further object of the invention to provide a halter having the foregoing characteristics and which yet is attractive, comfortable, easy to make and don and has no visual resemblance to a brassière.

Other objects of this invention will in part be obvious and in part hereinafter pointed out.

The invention accordingly consists of the features of construction, combinations of elements, and arrangement of parts which will be exemplified in the construction hereinafter described and of which the scope of application will be indicated in the claims.

In the accompanying drawings, in which is shown one of the various possible embodiments of this invention,

Fig. 1 is a front view of a feminine figure wearing a bathing suit including a halter embodying my invention;

Fig. 2 is a similar view of the halter, gathered up, however, to exercise uplift;

Fig. 3 is a side view of the figure shown in Fig. 1;

Fig. 4 is a plan view of the halter laid on a flat surface;

Fig. 5 is a front view of the halter as it appears when partially donned; and

2

Fig. 6 is an enlarged sectional view taken substantially along the line 6—6 of Fig. 5.

In general I achieve the several objects of my invention by providing a halter which comprises a scanty brassière of any suitable design including a pair of bust cups and means to hold said cups in position on a wearer. Each bust cup has associated therewith an elongated fabric band having an end secured to the outer side edge of the cup with the longitudinal axis of the band directed downwardly at an angle to extend generally below the opposite bust cup. When the halter is donned the bands are crossed at the front of the wearer, brought around to the wearer's back and the ends thereof secured together. Each band is arranged to cover a portion of the underside of the opposite bust cup and to overlie a part of the rib cage immediately below said bust cup. In this fashion the bands serve to prevent exposure of those parts of the undersides of the bust which creep out from beneath the bust cups. The portion of each band overlying its associated bust cup may be shaped approximately to the contour of the cup to enhance molding and control of the bust; and, in addition, means may be provided to gather and lift the bands where they cross and thus further uplift and control the bust. The halter may form the upper half of any two piece outer garment as, for example, a bathing suit, sun suit, play suit or evening gown.

Referring now to the drawings Fig. 10 denotes a two piece bathing suit comprising a conventional pair of trunks 12 and a halter 14 embodying my invention. As indicated above, the halter includes a scanty brassière 16 and a pair of elongated bands 18, 20.

Any conventional scanty brassière may be employed and, by way of example, I have shown a simple brassière including two bust cups 22, 24. Each bust cup consists of an upper panel 26 and a lower panel 28 secured to each other by a central line of stitching 30. The panels are shaped and stitched together in a manner well known to the art to provide a cup shaped configuration of desired contour. To best illustrate the basic principle underlying the invention the bust cups have been shown as having pentagonal front outlines. Thus the outer side edges 32 of the bust cups are distinctly indicated, as are the inner side edges 34, the bottom edges 36 and the upwardly tapering top edges 38.

The two bust cups are stitched together along their inner side edges 34.

Suitable means is provided to hold the bust cups in position on a wearer's torso, such means com-

prising a pair of straps 40, 42, each stitched at an end thereof to one of the outer side edges 32 of a bust cup. In the illustrated example said straps are shown as long enough to be tied together at the back of the user, but it will be understood that, if desired, other conventional fastening means may be employed, for instance hooks and eyes, laces, or a short length of elastic permanently secured to the other ends of both straps.

The brassière may also include a pair of shoulder straps 44, 46.

The bands 18, 20 are of fabric and preferably are somewhat resilient so that they can be pressed tightly against the bust without disturbing the desired contour imparted thereto by the brassière. To this end the bands may be made from a fabric such as "lastex," having elastic strands in the warp and weft, or from a knitted material, or they may simply consist of elongated woven fabric bands with the longitudinal axes thereof on a bias to the warp and weft. An end of each band is stitched to the outer side edge 32 of an associated bust cup with the longitudinal axis of the band extending downwardly at an angle such that the band will cross over in a direction generally toward and below the apex of the opposite bust cup, this disposition of the bands being shown in Fig. 4.

It may be mentioned that in Fig. 5 the crossed position of the bands is not apparent, the bands being allowed to hang straight down in said figure so that the construction of the brassière might be shown more clearly.

Suitable means is provided to hold the bands tightly against the bust in their crossed arrangement, such means in the illustrated figures merely consisting in having the bands long enough to cross again at the back of the wearer and have their free ends tied together across the wearer's midriff in a knot 48. To expedite tying and reduce coverage the bands are tapered toward their free ends and their side edges stitched together beyond the crossed over portions to form tubes.

It will be understood that, as in the case of the straps 40, 42 any other conventional means may be employed to hold the bands in their proper position.

Particularly good results are obtained when the bands are quite wide and for this reason I may make each band broad enough to be stitched to the top edge 38 of its associated bust cup. With this width of band it is only necessary to stitch the band to the outer sloping portion 38a of the top edge; however, appearance is better served if the band is stitched to the inner sloping portion 38b of said top edge as well.

To don the halter the scanty brassière 16 is first put on in the usual manner. Then the bands 18, 20 are crossed and so arranged that each passes over the bust cup opposite to that to which it is attached and the upper edge 50 thereof lies below the apex of said opposite cup. A desirable arrangement of the bands is that in which each upper band edge crosses the bottom edge 36 of the opposite bust cup at about its midpoint, this disposition being shown in Fig. 1. It will thus be seen that the portion of a band adjacent its associated bust cup affords coverage for that part of the underside of a breast which creeps out from beneath the bottom edge 36 of said cup and that additional coverage is afforded for the inner part of the same underside by that portion of the other band which crosses over the lower part of said bust cup.

Desirably the secured end of each band is gored,

pleated, darted or tucked as illustrated at 52 so that said end will better conform to the shape of the underlying bust cup.

The bands also may be employed to enhance the uplift and control of the brassière 16 by gathering the bands into a small compass where they cross between the cups and, preferably, raising the gathered portion close to the top edges of the bust cups. For this purpose I provide a tape 54 stitched intermediate its ends to the center of the top edge of the brassière (see Fig. 5). When not in use said tape may be tucked between the brassière and bust. To employ the tape one end thereof is passed down inside the brassière and in back of the crossed portions of the bands. This end is then brought back up and tied to the other end, thus gathering and lifting the bands where they cross, as shown in Fig. 2.

It will thus be seen that I have provided a halter which achieves the several objects of this invention and is well adapted to meet the conditions of practical use.

As various possible embodiments might be made of the above invention, and as various possible changes might be made in the embodiment above set forth, it is to be understood that all matter herein described or shown in the accompanying drawings is to be interpreted as illustrative and not in a limiting sense.

Having thus described my invention, I claim as new and desire to secure by Letters Patent:

1. A halter comprising a brassière including a pair of bust cups and means to hold the same in position on a wearer's torso, and a pair of elongated fabric bands distinct from said bust cups and independent of the means for holding said cups in position, each of said bands being associated with one of said bust cups and secured to the outer side edge of said cup with the longitudinal axis of the band directed downwardly at an angle such that the band extends in a direction toward and below the apex of the opposite bust cup whereby in use the bands will cross between the breasts and each band will cover and extend below the bottom edge of its associated bust cup and an inner portion of the bottom edge of the opposite bust cup, and means to hold the bands tightly against the bust in such position.
2. A halter comprising a scanty brassière including a pair of bust cups and means to hold the same in position on a wearer's torso, and a pair of elongated resilient fabric bands distinct from said bust cups and independent of the means for holding said cups in position, each of said bands being associated with one of said bust cups and secured to the outer side edge of said cup with the longitudinal axis of the band directed downwardly at an angle such that the band extends in a direction toward and below the apex of the opposite bust cup whereby in use the bands will cross between the breasts and each band will cover and extend below the bottom edge of its associated bust cup and an inner portion of the bottom edge of the opposite bust cup, said bands being long enough to extend around at least to the back of a wearer, and means to hold the bands tightly against the bust in such position.
3. A halter comprising a brassière including a pair of bust cups and means to hold the same in position on a wearer's torso, and a pair of elongated fabric bands distinct from said bust cups and independent of the means for holding said cups in position, each of said bands being associated with one of said bust cups and secured

to the outer side edge of said cup with the longitudinal axis of the band directed downwardly at an angle such that the band extends in a direction toward and below the apex of the opposite bust cup whereby in use the bands will cross between the breasts and each band will cover and extend below the bottom edge of its associated bust cup and an inner portion of the bottom edge of the opposite bust cup, means to hold the bands tightly against the bust in such position, and means to gather and lift the crossed portions of the bands.

4. A halter comprising a brassière including a pair of bust cups and means to hold the same in position on a wearer's torso, and a pair of elongated fabric bands distinct from said bust cups and independent of the means for holding said cups in position, each of said bands being associated with one of said bust cups and secured at an end thereof to the outer side edge and top edge of said cup with the longitudinal axis of

the band directed downwardly at an angle such that the band extends in a direction toward and below the apex of the opposite bust cup whereby in use the bands will cross between the breasts and each band will cover and extend below the bottom edge of its associated bust cup and an inner portion of the bottom edge of the opposite bust cup, and means to hold the bands tightly against the bust in such positoin.

15

20

5. In combination with a brassière including a pair of bust cups, a pair of elongated fabric bands each associated with but distinct from one of said bust cups, each said band being secured to its associated bust cup adjacent an end of the band and substantially fully covering said bust cup, the remainder of each said band being free of said bust cup, each said band extending in a general direction toward the other bust cup, and means to hold said bands in position on a wearer's torso.

VALERIE NAGY.
